DEVICE FOR FORMING PLATE GANGS FOR
MULTICOLOR PRINTING

Bernard F. Heck, St. Paul, Minn.

Application June 27, 1932, Serial No. 619,367

14 Claims. (Cl. 113—99)

My invention relates to an improved device for forming plate gangs for multi-color printing and has for an object thereof to provide a novel and effective structure for carrying out a method for forming plate gangs which constitutes the subject matter of my co-pending application, Serial No. 690,687.

In said method, the several plates of the different gangs for different colors are successively grouped upon a device having individual gauge members for the individual plates of a gang, said method involving the attachment of the plates of each gang in their gauged relation to a suitable backing while disposed upon said device so that the corresponding plates in the several gangs of the set have identically the same relation with respect to their companion plates in their respective gangs.

Another object of the invention resides in providing a device for carrying out my method in which gauge pins are adjustably positioned to be arranged in any desired manner to accommodate electrotype plates of different widths and different lengths.

A still further object of the invention resides in providing in said device a bed and guides mounted thereon and in providing a number of supports movable along said guides and carrying gauge pins for engagement with gauge holes in the electrotype plates.

A feature of the invention resides in constructing each guide with a groove and in providing blocks slidably adjustable therein and on which gauge pins are mounted.

Another object of the invention resides in providing locking means for securing the slidable blocks relative to their respective guides.

An object of the invention resides in making said grooves and blocks of a dovetailed construction and in providing screws threaded into said blocks for locking engagement with the guides.

An object of the invention resides in arranging the bed and guides to provide a space to receive a mounting or backing to which the plates are to be attached.

A feature of the invention resides in securing the plates to a backing by means of solder keys.

Another object of the invention resides in providing a way on said bed slideable toward and from one of the guides and in mounting the other guide for sliding movement along said way.

Other objects of the invention reside in the novel combination and arrangement of parts and

in the details of construction hereinafter illustrated and/or described.

In the drawings:

Figs. 1, 2, 3 and 4 are perspective views of ordinary engraved plates from which electrotype plates used in color printing are made, one of such plates being employed for each of the different colors used.

Fig. 5 is a view of the ultimate print.

Fig. 6 is a perspective view of an electrotype plate made from an engraved plate, as shown in Fig. 1, and having gauge holes drilled therein.

Fig. 7 is a perspective view of a mounted gang, the several electrotype plates comprising said gang being like that shown in Fig. 6.

Fig. 8 is a sectional view taken on line 8—8 of Fig. 7.

Fig. 9 is a perspective view of an assembling device capable of use for carrying out my improved method.

Fig. 10 is a fragmentary sectional view taken as on line 10—10 of Fig. 11 and drawn to a larger scale.

Fig. 11 is an elevational sectional view taken as on line 11—11 of Fig. 9 and drawn to a larger scale.

Fig. 12 is a perspective view of one of the gauge blocks employed.

In making engravings to be used in forming electrotype color plates, the engraver customarily cuts gauge marks at top and bottom of the engravings which marks show on the electrotype plates and are used in stationing the different color plates in a proof press to register the different prints taken therefrom.

Upon being satisfied with the showing made by the electrotype plates in the color proof press, the electrotyper has then to mount like plates in gangs, it being his desire, of course, that the corresponding plates of the several gangs occupy corresponding relations with respect to the companion plates in their respective gangs. Ordinarily, the different electrotype plates of the several gangs are as accurately as possible similarly trimmed with respect to the gauge marks thereon with the view of assembling the plates of each gang in abutting relation on a mounting block. In following this practice, errors of more or less magnitude occur and are sometimes greatly multiplied before the individual plates of a gang are ultimately secured to their respective mounting blocks. Due to such errors it is impossible invariably to secure perfect register of prints from all of the

5

corresponding plates of the different gangs employed in a multi-color job. The employment of my invention in forming sets of color gangs practically eliminates all chance of error and results in substantially accurate register, regardless of the number of plates incorporated in each gang.

The device shown in the drawings includes a bed 10 supported on legs 12, the bed 10 being of any suitable length. Upon said bed 10 and at the forward edge thereof is mounted a front guide 13 which consists of a bar of metal formed from end to end thereof with a dovetailed groove 14 opening at the top of the bar. This guide may be integral with the bed 10 or may be separately constructed and rigidly secured thereto in a permanent manner.

Formed in the bed 10 at right angles to the guide 13 are parallel slots 15. A way 18 slidably disposed upon the bed 10 overlies the slots 15, said way being substantially the same length as the guide 13. This way 18 is formed with threaded bores 19, as best shown in Figs. 10 and 11, to receive clamping bolts 20 which extend through the slots 15 and serve to hold said way in various adjusted positions with respect to the guide 13.

The way 18 is constructed with a dovetailed tongue 22 extending along the upper side thereof, said tongue being adapted to be received in a dovetailed slot 23 formed in the underside of a guide 24 similar in form to the guide 13. The guide 24 is also provided with a dovetailed slot 25 corresponding with the dovetailed slot 14 of guide 13. The guide 24 may be locked against movement with respect to the way 18 by a number of thumb screws 34 threaded into said guide from the back thereof. These thumb screws 34 engage a gib 35 disposed within the slot 23 and extending along one edge of the tongue 22. As said screws 34 are tightened the gib 35 is forced against the tongue 22 which holds the guide 24 from movement on the way 18.

In conjunction with the two guides 24 and 13 a number of supports 26 are employed which are constructed from blocks of metal beveled along the surfaces 57 and 58 thereof to snugly fit within the two grooves 14 and 25 of the guides 13 and 24. These blocks are inserted endwise into said grooves and may be slid therealong to occupy any desired adjusted position therein. Each of the blocks 26 is provided at the top thereof with a gauge pin 27 and is formed with a threaded bore as at 29 to receive a set screw 30. The lower end of this bore is reduced in diameter, as shown, providing an internal shoulder 60. A seating element 32, occupying the reduced portion of the bore 29, has a head 61 contained within the bore proper which cooperates with the shoulder 60 and keeps the seating element 32 from becoming displaced from the block 26 at such time as said block may be removed from its guide. The set screw 30 may be constructed with a square hole 31 at its upper end by means of which a suitable wrench may be applied thereto to turn the same. When one of the gauge blocks 26 is mounted in either of the grooves 14 or 25, said block may be firmly locked in position by turning the screw 30 down against the seating element and thus forcing said element against the lower wall 33 of the guide. This urges the beveled walls 57 and 58 of the block into engagement with the adjacent

walls of the slots 14 or 25 and holds the block locked against movement.

For the purpose of illustrating the application of my invention, I have shown in Fig. 5 an ultimate print to be printed and in Figs. 1 to 4 inclusive, the various engraved plates from which electrotypes used in printing this figure would be made. The print illustrated is printed in four colors, blue, red, gold and black and the engraved plates for these colors are designated by the reference characters 36, 37, 38 and 39 in Figs. 1 to 4 respectively. A number of the electrotypes made from plate 36 are indicated at 36a, 36b and 36c in Fig. 7, a similar electrotype being indicated at 36a in Fig. 6. Corresponding electrotype plates made from the engraved plates 37, 38 and 39 would be required, of course, to complete the set. On the body 41 of each of the various electrotypes is a raised portion 40 corresponding with the raised portion 40a of the engraving from which it was made. The metal of the body 41, except at the raised portion thereof is "dead metal", its primary purpose being to provide means for attaching the plate proper to the mounting therefor. In this "dead metal", the gauge marks 42 and 43 (Fig. 6) appear in simulation of the corresponding gauge marks 42a and 43a (Fig. 1) formed in the original engraving.

In multi-color proof printing, it has been the practice to some extent to drill gauge holes in the electrotype plates, such holes having a definite relation with respect to the gauge marks thereof and to successively mount such plates on guide pins in the bed of a proof press whereby registered printing of the various plates could be accurately carried out to form the proof print. In the present invention, such gauge holes may be utilized. In Fig. 6, I have shown a plate 36a in which has been drilled two gauge holes 44 and 45. In thus drilling a plate in the type of machine available for the purpose, the plate is mounted upon a support and adjusted under a locating glass until one or the other of the gauge marks 42 or 43, as the case may be, registers with a cross hair associated with said glass. When the plate is properly located, a drill is brought into action, said drill being so mounted and operated as to drill the holes at predetermined locations with respect to the gauge mark of the plate upon which sight is taken. All the electrotype plates taken from the engravings 36, 37, 38 and 39 are drilled in the same manner with respect to each gauge mark, each plate then having gauge holes 44 and 45, the holes in each plate being located in identically the same relation with respect to their gauge marks 42 and 43. In addition to the gauge holes two holes 50 are drilled in the "dead metal" of the plates for a purpose soon to be explained.

In the mounting of the plates upon the assembling device the following procedure is employed: The thumb screws 34 and the bolts 20 are first loosened so that the guide 24 may be moved in two directions upon the bed 10. A block 26 is next inserted in the slot 14 of guide 13 at approximately the desired locality. This block is then locked in place through its set screw 30. In a similar manner another block is mounted in approximately the proper location in the guide 24 and locked in place. One of the plates for example 36a, is then placed upon the assembling device and the register holes 44 and 45 thereof caused to receive the gauge pins of 75

the two blocks mounted in the guides 13 and 24. The plate 36a is then squared up with respect to the guide 13, the guide 24 being moved lengthwise on the way 18 and said way being moved transversely on the bed 10 as may be required in accomplishing the purpose. When the guide 24 is properly located all of the screws 34 and the bolts 20 are tightened to hold the parts 24 and 18 rigidly in position. If desired, a second plate may be temporarily used to procure parallelism between the two guides. In such case, this plate would be mounted upon two gauge pins situated at the far ends of the guides 24 and 13, whereby parallel spacing of the guides could be readily procured. With the guide 24 properly positioned and clamped, additional gauge blocks are applied and secured to the guides 13 and 14, the distances between gauge pins 27 in the blocks 26 in each guide being made sufficient to accommodate the width of the plates and being calipered for accuracy. Thus, all of the blocks 26 for all of the electrotypes to be incorporated in a gang are assembled and held in selected relation with respect to each other.

With the blocks 26 in place in the guides 13 and 24, the remaining plates going to make up the gang are applied, one to each pair of gauge pins, and pressed down to rest upon the upper edges of said guides 13 and 24. In Fig. 9, the plates 36a, 36b and 36c, made as from the engraving 36, have been illustrated as mounted upon the device. A filler block 48 of wood is then inserted between the two guides 13 and 24 and beneath the various plates 36a, 36b and 36c. Upon this block is placed a metal backing 49 which snugly underlies said plates. Solder is then flowed into the holes 50 forming solder keys 51 securing the plates to the backing 49. The structure thus formed is removed en-bloc from the gauge pins 27 without disturbing the position of the blocks 26, the plates and backing being then trimmed down to the proper dimensions, the end portions of said plates containing the gauge marks and gauge holes being cut away to complete the construction of the gang.

The several plates for another color gang are placed upon the assembling device, the same being readily applied to the gauge pins 27 without disturbing the position of the blocks 26. These plates are then secured to a backing therefor and then removed from the assembling device and trimmed as in the case of the gang first described. The same operation is repeated for the several plates of each of the remaining color gangs, each gang being built up without changing the position of the pins 27. After all of the gangs have been completed it will be found that each plate of each gang will accurately register with the corresponding plate of each of the other gangs so that impressions may be taken from all of the plates and brought into absolute register.

A set of color gangs, made through the use of my device as hereinabove described, would be employed preferably as master plates for making other electrotypes. If desired, however, the different gangs of a set, as I construct them, may themselves be used for printing, in which case they would be attached to a suitable wood block. And, too, original hand engraved plates, zinc etchings, copper etchings, photo engravings and stereotypes may be assembled in gangs in accord-

ance with the present invention to be used for printing or duplicating.

With my invention the various electrotypes of a gang may be mounted accurately in predetermined relation with respect to one another. The corresponding plates of the different gangs have exactly the same relation with respect to the other plates of their respective gangs so that absolute register is procured. Even though an irregularity occurs, for example, as in the clamping of the blocks 26 in the guides 13, 24, the same irregularity occurring in each gang will not affect register in printing. The gangs can be assembled quickly and easily and the plates mounted upon their respective backings without disturbing the plates in their acquired relation and without disturbing the positions of the pins 27. The assembling device is extremely simple in construction and is not only easy to use when once adjusted, but also readily adjustable to accommodate various sizes of plates. There is nothing in the device to get out of order and with the movable parts locked in position, they remain immovable throughout the repeated operations entailed in completing the gangs of a set. The invention admits of the use of the conventional plate drilling machines. As many plates as desired can be associated in a single gang without accumulative error and the relation between plates of each gang of a set will be identical in each instance.

Changes in the specific form of my invention, as herein disclosed, may be made within the scope of what is claimed without departing from the spirit of my invention.

Having described my invention, what I claim as new and desire to protect by Letters Patent is:

1. A device for forming plate gangs for multi-color printing from plates having gauge holes therein, said device comprising a bed having supports thereon, and gauge pins on said supports for engagement with corresponding gauge holes in the plates of the various gangs, said supports being spaced apart to receive there-between a backing for the plates inserted between said plates and the bed.

2. A device for forming plate gangs for multi-color printing from plates having gauge holes therein, said device comprising a bed, a guide on said bed, another guide on said bed spaced from said first guide, means for guiding one of said guides for movement toward and from the other guide, supports movable along said guides and gauge pins on said supports for cooperation with the gauge holes in plates of a gang.

3. A device for forming plate gangs for multi-color printing comprising a bed, a guide on said bed, a way, a second guide slidable along said way, means for guiding said way and second guide for movement toward and from said first guide, supports movable along said guides and gauge pins carried by said supports.

4. A device for forming plate gangs for multi-color printing comprising a bed, a guide on said bed, a way parallel with said guide, means for guiding said way for movement in a direction at right angles to said guide, a second guide slidable along said way in a direction parallel to said first named guide, supports slidable along said guides and gauge pins carried by said supports.

5. A device for forming plate gangs for multi-color printing comprising a bed, means on said bed providing a fixed groove, means on said bed

- providing a second groove parallel with said first groove, blocks slideable along said grooves, gauge pins carried by said blocks, and means for locking said blocks from movement with respect to said grooves. 5
6. A device for forming plate gangs for multi-color printing comprising a bed, means on said bed having dovetailed grooves therein, a number of dovetailed blocks slideable along said grooves, gauge pins carried by said blocks, and locking devices carried by said blocks for urging the same into engagement with the walls of said grooves. 10
7. A device for forming plate gangs for multi-color printing comprising a bed, means on said bed having dovetailed grooves therein, a number of dovetailed blocks slideable along said grooves, gauge pins carried by said blocks, each block having a set screw threaded thereinto for exerting pressure against a wall of its respective groove. 15
8. A device for forming plate gangs for multi-color printing comprising a bed, a guide on said bed having a dovetailed groove therein, said bed having slots along the same extending at right angles to said guide, a way parallel with said guide and slideable along said slots in a direction toward and from the guide, a second guide slideable along said way and having a dovetailed groove therein, blocks slideable along said dovetailed grooves, gauge pins carried by said blocks and means for locking said blocks from movement with respect to said grooves. 20
9. A device for forming a plate gang from plates having gauge means thereon, said device comprising a bed having supports thereon, one of said supports being movable relative to the other to vary the distance therebetween, and gauge means on one of the supports formed for cooperation with the gauge means on the plates to locate said plates in definite predetermined relation. 25
10. A device for forming sets of plate gangs for multi-color printing from plates having gauge means thereon, said device comprising a mounting and gauge means supported thereby, 30
- said gauge means being formed for cooperation with the gauge means of all of the plates of a gang, whereby the plates of the several gangs in a set may be located in the same definite relationship in each gang, said gauge means being supported on said mounting for adjustment to accord with the varying dimensional requirements of plate gangs of different sets. 35
11. A device for forming plate gangs for multi-color printing from plates having gauge holes therein, said device comprising a pair of supports, one thereof being movable for relatively disposing said supports initially to similarly accommodate the plates of each gang of a set, and gauge pins on said supports for engagement with the gauge holes in the plates of a gang. 10
12. A device for forming plate gangs for multi-color printing from plates having gauge holes therein, said device comprising a bed, a guide on said bed, a number of supports individually movable along said guide, means for locking the individual supports with respect to said guide, each support having a gauge pin thereon for engagement with the gauge holes in the corresponding plates of the various gangs of a set. 15
13. A device for forming plate gangs for multi-color printing from plates having gauge holes at the ends thereof, said device comprising a bed, gauge pins, means for supporting the gauge pins in spaced rows above said bed and in position for cooperation with the gauge holes in plates of a gang, and means for supporting the plates of a gang in their cooperative relation with said pins at a fixed elevation above said bed. 20
14. A device for forming plate gangs for multi-color printing from plates having gauge means thereon, said device comprising a pair of spaced supports for the plates of a gang, and gauge means on one of said supports adapted to cooperate with the gauge means on the plates of the various gangs and thereby provide for a definite predetermined relationship between plates in the different gangs. 25

45 BERNARD F. HECK.
